US00D411004S

United States Patent [19]

Muller et al.

[11] Patent Number: Des. 411,004

[45] Date of Patent: ** Jun. 15, 1999

[54] **RADIO FREQUENCY GENERATOR FOR MEDICAL DEVICES**

[75] Inventors: **Peter H. Muller**, Los Gatos; **David Rapp**, Mountain View; **Rick T. Smethers**, Fremont, all of Calif.

[73] Assignee: **Somnus Medical Technologies, Inc.**, Sunnyvale, Calif.

[**] Term: **14 Years**

[21] Appl. No.: **29/075,144**

[22] Filed: **Aug. 13, 1997**

[51] LOC (6) Cl. **24-02**

[52] U.S. Cl. **D24/107**

[57] CLAIM

The ornamental design for a radio frequency generator for medical devices, as shown and described.

DESCRIPTION

FIG. 1 is an isometric view of the radio frequency generator for medical devices.

FIG. 2 is a front-elevational view of the radio frequency generator for medical devices.

FIG. 3 is a top plan view of the radio frequency generator for medical devices.

FIG. 4 is a bottom plan view of the radio frequency generator for medical devices.

FIG. 5 is a side-elevational view of the radio frequency generator for medical devices with the other side being identical; and,

FIG. 6 is a rear-elevational view of the radio frequency generator for medical devices.
